UNITED STATES PATENT OFFICE.

JAMES J. DILKS, OF PHILADELPHIA, PENNSYLVANIA.

MACHINE FOR SECURING REINFORCING-BANDS TO FILM-STRIPS.

1,294,882.

Specification of Letters Patent. Patented Feb. 18, 1919.

Application filed April 9, 1918. Serial No. 227,483.

To all whom it may concern:

Be it known that I, JAMES J. DILKS, a citizen of the United States, residing in Philadelphia, Pennsylvania, have invented 5 Improvements in Machines for Securing Reinforcing Bands to Film-Strips, of which the following is a specification.

The object of my invention is to provide simple and effective means for applying 10 to the perforated edge or edges of a moving picture film an effective reinforcing device therefor, an object which I attain in the manner hereinafter set forth, reference being had to the accompanying drawings, 15 in which—

Figure 1 is a diagrammatic view showing, partly in elevation and partly in section, and partly in full and partly in dotted lines, mechanism devised for applying the 20 reinforcing strip to the film;

Fig. 2 is an enlarged view, partly in elevation and partly in section, of those elements of the machine whereby the securing of the reinforcing strip to the film is effected;

Fig. 3 is a top view of one edge of the film with the reinforcing strip secured thereto;

Fig. 4 is a similar view illustrating the 40 first steps in the operation of securing the reinforcing strip to the film, and

Fig. 5 is a longitudinal sectional view illustrating a modification of my invention.

Moving picture film is provided, near each edge, with a longitudinal row of perforations for engagement with the toothed feed wheels whereby intermittent forward feed of the film in the camera or projector is effected. Owing to the delicate character of the film it is desirable that the perforated portions thereof should be strengthened or reinforced in order to enable them to withstand the strains to which they are subjected, and it is the object of my invention to accomplish this reinforcement.

The reinforcing strip 1, which may be of any desired flexible material of sufficient strength, is applied to one face of the film 2 so as to cover the perforated portion of the same, as shown in Fig. 4, and pairs of oppositely facing wings 3 are bent downward from the strip and caused to project through the perforations 4 in the film, as 55 also shown in said figure and in Fig. 2. The tips of the wings 3 are then bent one in

one direction and the other in the opposite direction back toward that face of the film opposite the one against which the reinforcing strip is disposed, as shown at 60 the left hand side of Fig. 2, so that the reinforcing strip is clenched to the film, the wings 3, however, being so disposed in respect to the ends of the perforations 4 in the film as to be free from contact with 65 said ends, as shown in Figs. 2 and 3, in order that the pull of the toothed feed wheel of the camera or projector will be exerted wholly upon the wings of the reinforcing strip and not upon the forward 70 edge of the perforation in the film, the latter being, consequently, relieved from all direct strain.

The formation of the wings 3 upon the reinforcing strip 1 is effected by means of 75 a chisel-pointed punching die 7 (Fig. 2) which acts upon said strip as the latter and the film 2 are supported upon a rotary die 5, in which are sockets 6, as shown in Fig. 2, the chisel point of the die 7 first 80 forming a transverse incision α in the reinforcing strip 1, as shown at the right hand side of Fig. 4, and the continued downward movement of the die then pressing the material on each side of said incision downward through the perforation in the film, as shown in Fig. 2 and at the left hand side of Fig. 4.

At a point of rest somewhat farther along in the travel of the film, the downwardly 90 projecting ends of the wings 3 are acted upon by a clenching die 8 which co-operates with an upper die 9 bearing upon the face of the reinforcing strip, as shown at the left hand side of Fig. 2, whereby the ends 95 of the wings 3 are bent one in one direction and the other in the opposite direction back against the under face of the film and securely clench the reinforcing strip thereto.

The feeding of the film and reinforcing strip through the strip securing mechanism is effected by a succession of intermittent forward movements of the proper extent, the perforated portion of the film being engaged by toothed rollers 10 and 11, as 100 shown in Fig. 1, to which rollers intermittent forward movements of partial rotation may be imparted in any desired manner, as, for instance, by means of ratchet wheels 12 which are acted upon by pawls 13 105 carried by levers 14 to which vibrating movement is imparted from an arm 15 on a

rock shaft 16 through the medium of connecting rods 17, as shown, by dotted lines, in Fig. 1.

5 Reciprocating movements are imparted to the punching die 7 and clenching die 8 by means of crank arms 18 on shafts 19, said crank arms being connected to the die carrying cross heads 20 by means of links 21, as shown in Fig. 1, the upper and lower shafts 10 19, being connected for joint and simultaneous operation by means of a connecting rod 22 which engages crank pins 23 on disks 24 secured to the shafts 19, as also shown, by dotted lines, in Fig. 1.

15 Intermittent forward movements are imparted to the rotary die 5 from the upper die-carrying cross head 20 through the medium of a rod 25, (shown, by dotted lines, in Fig. 1) said rod acting on a lever 26, 20 which is connected by a link 27 to one arm of a lever 28 mounted so as to rock on the shaft of the die 5, the other arm of said lever carrying a pawl 29 which engages the teeth of a ratchet wheel 30 on said die. Another 25 link 31 serves to connect the lever 26 to an arm 32 on the rock shaft 16 so as to impart the desired rocking movement to the latter.

By the use of the rotary die 5 the freeing of the projecting ends of the wings 3 from 30 the sockets 6 in said die is automatically effected as the die rotates, no raising of the film from the face of the die being necessary for this purpose, and by properly regulating the approach of the clenching die 8 35 to the die 9 the gage or thickness of the reinforced portion of the strip can always be accurately determined, or, if desired, this may be effected by means of a pair of gage rollers 33 and 34 between which the reinforced film passes after it has left the dies 8 and 9.

In the drawing I have only shown the application of the reinforcing strip to one edge of the film, but it can, of course, be applied 45 to both edges of the same, if desired, this involving no more than mere duplication of the punches and dies shown in Fig. 2.

Instead of clenching the tips of the wings 3 of the reinforcing strip directly upon the 50 under face of the film, as shown in Fig. 2, the film may have reinforcing strips upon both faces, as shown, for instance, at 1 and 1^a in Fig. 5, the reinforcing strip 1^a being provided with perforations coincident with 55 the perforations 4 in the film and the wings.

3 passing through the perforations in the film and in the reinforcing strip 1^a and having their tips clenched against the under face of said strip 1^a. The use of the reinforcing strip upon but one face of the film 60 has, however, proven to be amply sufficient in practice and is preferred.

I claim:

1. In apparatus for applying a reinforcing strip to a perforated film, the combination of a socketed rotatable die serving as a support for the reinforcing strip and film, means for imparting intermittent forward movements to the strip, film and die, and means, operative during the intervals between such movements, for driving wings from the reinforcing strip through the perforations in the adjacent film and for clenching said wings on the reverse face of the film. 70

2. In apparatus for applying a reinforcing strip to a perforated film, the combination of means for intermittently feeding forward the reinforcing strip and film, a supporting die for the same, means for rotating said die by intermittent movements of partial rotation coincident with the movements of the strip and film, a punch co-operating with said supporting die, a clenching device, and means for imparting movement to said punch and clenching device during the intervals between the feeding movements of the strip and die. 75

3. In apparatus for applying a reinforcing strip to a perforated film, the combination of means in feeding engagement with the strip and film at front and rear of the machine, a rotary die for supporting the strip and film at a point between said front and rear feeding devices, a punch co-operating with said die to form on the strip fingers projecting through the perforations of the film, a punch and die for clenching said fingers on the back of the film, and means for intermittently and synchronously operating the front and rear feeds and the supporting die and for synchronously operating said punching and clenching devices in the intervals between the successive feeds. 90

In testimony whereof I have signed my name to this specification in the presence of a subscribing witness.

JAMES J. DILKS.

Witness:

WILLIAM R. TRAUTSCHOLD.
